UNITED STATES PATENT OFFICE.

WALTER KIESER, OF CHARLOTTENBURG, GERMANY, ASSIGNOR TO GENERAL ELECTRIC COMPANY, A CORPORATION OF NEW YORK.

CENTRIFUGAL COMPRESSOR.

1,087,382.

Specification of Letters Patent. Patented Feb. 17, 1914.

Application filed June 6, 1911. Serial No. 631,591.

To all whom it may concern:

Be it known that I, WALTER KIESER, a citizen of Switzerland, residing at Charlottenburg, Germany, have invented certain new and useful Improvements in Centrifugal Compressors, of which the following is a specification.

This invention relates to centrifugal compressors and the object of the invention is the provision of improved means for circulating the cooling water used in such compressors to cool the air or other gases being operated upon by the removal of the heat of compression.

15 In the drawing illustrating one of the embodiments of the invention, Figure 1 is a partial cross section of a compressor taken on the line 1—1 of Fig. 2; Fig. 2 is a partial side view of a compressor with a portion 20 in section; and Fig. 3 is a diagrammatic view showing the circulation of the cooling water.

The compressor illustrated is a multistage compressor having a shaft 4 upon which 25 the impellers 5 of the several stages are mounted, the shaft being driven by any suitable motor. The impellers are separated from each other by diaphragms 6 secured in the casing 7. The casing is made in halves 30 to facilitate the assembling of the machine and the diaphragms 6 may also be made in halves as shown. Passages or conduits 8 convey the air through the diaphragms from the discharge of one impeller to the inlet of 35 the next impeller. During the flow through the passages 8, the air is cooled by water circulated over the outer walls of said passages by a pump or other means. Each dia- 40 phragm has in it a water chamber or chambers 9 of general semi-annular form located between the inner walls of the U-shaped bend in the passage 8 which receives the air discharged from one impeller and turns its direction through substantially 180° to lead 45 it toward the inlet of the next impeller.

Each diaphragm 6 also contains another water chamber that is subdivided into compartments 10, and the water in this last mentioned chamber acts upon adjacent walls 10^a 50 that lie between and opposite the wall cooled by the water in the chamber 9 of said dia- phragm and the wall cooled by the water in the chamber 9 of the next adjacent dia- phragm to the right. At least one of the 55 cooling chambers which adjoin the directing

passages 8 is subdivided, and the subdivisions are arranged either wholly or partially in series relation as to the flow of water by means of the cooling chambers provided on the other side of the directing passages. 60 Each chamber or compartment 10 occupies a quarter of a diaphragm, being bounded by the radially disposed walls 11 extending from the inner wall 12 of the chamber to the casing. Other radially arranged walls or 65 partitions 13 extend from the wall 12 to within a short distance of the casing, a space 14 being provided between the ends of the walls and the casing through which the water flows. Alternating with the parti- 70 tions 13 and the end walls 11 are other ra- dial partitions 15 which terminate a short distance from the wall 12 so as to leave a space 16 through which the water flows. In this manner a zigzag or tortuous channel 75 for the water comprising a plurality of sec- tions or passes is provided which leads from one end of the chamber or compartment 10 to the other. The chambers 9 and compart- 80 ments 10 in each diaphragm 6 are connected by passages 17 formed in the members or 85 guide vanes 18 that extend across the pas- sages 8 and as shown serve as guide vanes for the air, one of said passages 17 connect- 90 ing each section of the zigzag path or chan- nel with the chamber 9.

The diaphragms are arranged in series relation as to the general flow of the cooling water. Water is supplied to the right- 95 hand compartment 10 in a given diaphragm, say, (see Fig. 1) by pipes 19 and flows through the zigzag channel over one-quarter of the diaphragm. At the same time, the water flows from the chambers or compart- 100 ments 10 through the passages 17 arranged at intervals along the tortuous channel and enters the chamber 9 which extends over one-half of the diaphragm. The course of the water is then from one end of the cham- 105 ber 9 toward the other and through the pas- sages 17 at the left of said diaphragm 6 in Fig. 1 into the zigzag channel leading from the middle of the upper half of the dia- phragm to the pipe 20 which conveys water to the next diaphragm or from the last dia- phragm to some suitable receptacle that re- 110 ceives the discharge from the compressor. If desired, the chambers 9 and 10 can be extended over different arcs from those illus- trated. For example, the chamber 10 might

extend from one end to the other of the diaphragm, and the chamber 9 be extended entirely around the compressor by connecting the upper and lower parts thereof.

5 By the arrangement described, the cooling chambers are disposed partly in parallel and partly in series relation; all of the cooling water is forced to pass through the cooling chamber of a diaphragm which 10 forms the connection between the chambers in said diaphragm which are separated from it by the air passages in the diaphragm, and the temperature of the opposite chambers is kept approximately the same, there- 15 by improving the action of the compressor. If any clogging in the connecting passages occurs, it can be readily detected from the decrease of the discharge.

In accordance with the provisions of the 20 patent statutes, I have described the principle of operation of my invention, together with the apparatus which I now consider to represent the best embodiment thereof; but I desire to have it understood that the 25 apparatus shown is only illustrative, and that the invention can be carried out by other means.

What I claim as new and desire to secure by Letters Patent of the United States, is,—

30 1. In a centrifugal compressor, the combination of rotary impellers, diaphragms between the impellers having passages that direct the air or gas from one impeller to another, cooling water chambers in the dia- 35 phragms that are arranged on opposite sides of the passages, at least one of said chambers being subdivided into compartments and guide vanes in said passages, there being passages through the guide vanes 40 grouped in parallel relation to each other as to flow and connecting the compartments of one chamber through the other chamber so that cooling water flows through the compartments in series relation.

45 2. In a centrifugal compressor, the combination of rotary impellers, diaphragms between the impellers having passages that direct the air or gas from one impeller to another, guide vanes extending across the 50 passages, and cooling water chambers in the diaphragms that are arranged on opposite sides of the passages, at least one of the chambers being subdivided into compartments, there being passages in the vanes 55 arranged in parallel relation as to flow that connect the chambers so that cooling water flows from a compartment of one chamber to and through the opposite chamber and back to another compartment of the 60 first chamber.

65 3. In a centrifugal compressor, the combination of rotary impellers, diaphragms between the impellers having passages that direct the air from one impeller to another, guide vanes arranged in the passages, and

cooling water chambers in the diaphragms that are arranged on opposite sides of the passages, one of said chambers being subdivided into compartments that extend over a given arc while the opposite chamber has compartments extending over substantially twice that arc, there being passages through a plurality of said vanes that are arranged in parallel relation as to flow for conveying water from one of the smaller compartments 70 into a larger compartment; and other pas- 75 sages through a plurality of the vanes also arranged in parallel relation as to flow for conveying water from said larger compartment to one of the smaller compartments that is arranged next to the first smaller compartment.

4. In a centrifugal compressor, the combination of rotary impellers, diaphragms between the impellers having passages that 80 direct the air from one impeller to another, 85 guide vanes in the passages, cooling water chambers in the diaphragms on one side of the passages, means for directing the water in a tortuous path through said chambers over the walls of the passages, and cooling water chambers on the opposite side of the passages, there being passages extending through the vanes that connect the first and second chambers, said vane passages 90 being arranged in parallel relation to each other as to flow.

5. In a centrifugal compressor, the combination of rotary impellers, diaphragms between the impellers having passages that 100 direct the air from one impeller to another, 105 guide vanes arranged in said passages, cooling water chambers in the diaphragms on one side of the passages, overlapping parti- 110 tions extending from opposite sides of the chambers part way across said chambers to direct the water in a zigzag path through the chambers, and cooling water chambers on the opposite side of the passages, there being passages through the guide vanes 115 grouped in parallel relation to each other that connect the first and second chambers in series relation as to flow.

6. In a centrifugal compressor, the combination of a casing, rotary impellers therein, diaphragms between the impellers having passages that direct the air from one impeller to another, there being guide vanes in the passages and a cooling water chamber in each diaphragm that is arranged on 120 one side of the passage therein and is subdivided into a plurality of adjoining compartments, there being partitions in the compartments that direct the cooling water in a zigzag path through said compartments, and there being a cooling water chamber in the diaphragm that is arranged on the opposite side of the passage from the chamber aforesaid, there being passages through the vanes that connect each com- 125 130

partment with said chamber so that the water flows first to one compartment, then to the chamber, and from the chamber to the next compartment, each time through a plurality of said vane passages in parallel.

7. In a centrifugal compressor, the combination of rotary impellers, diaphragms between the impellers having passages that direct the air from one impeller to another, a cooling water chamber arranged on one side of the passage in a diaphragm that is subdivided into a plurality of adjoining compartments, partitions in the compartments that direct the cooling water through a compartment in a zigzag channel comprising a plurality of sections, a cooling water chamber in the diaphragm that is arranged on the opposite side of the passage from the chamber aforesaid, and means that extends across the air passage aforesaid and connects said chamber with each section of the zigzag channel in such compartment and with the adjacent compartment so that the water entering one compartment flows through a portion of said means to the chamber and from said chamber through another portion of said means into the next compartment.

8. In a centrifugal compressor, the combination of a casing, rotary impellers, diaphragms mounted in the casing between the impellers and having passages that direct the air from one impeller to another, said diaphragms being made in sections, a plurality of cooling water chambers or compartments in a given section that are arranged on one side of the passage, partitions in each chamber that direct the water through the chamber in a zigzag path comprising a plurality of sections, a single cooling water chamber in said diaphragm section that is arranged on the opposite side of the passage, conduits extending across the passage that connect each section of the zigzag path with said single chamber, means supplying water to the first of said plurality of chambers, and means conveying water from the last of said chambers, so that the water flows through a plurality of said conduits in parallel between said single chamber and each of the first mentioned chambers.

9. In a centrifugal compressor, the combination of a casing for the compressor that has a cylindrical interior, rotary impellers, diaphragms having passages that direct the air from one impeller to another, said diaphragms being mounted in the casing between the impellers and made in halves, there being two cooling water chambers or compartments in each half diaphragm that

are arranged on one side of the passage, radial partitions in the chambers that direct the water in a zigzag channel comprising a plurality of sections from one end 65 of each chamber to the other, a single cooling water chamber in said half diaphragm that is arranged on the opposite side of the passage, conduits extending across the passage and forming a connection between each 70 section of the zigzag channels and said chamber, a conduit supplying water to one of said two chambers, and a conduit for conveying water from the other chamber, so that the water flows through a plurality of 75 said conduits in parallel between said single chamber and each of the first mentioned chambers.

10. In a centrifugal compressor, the combination of rotary impellers, diaphragms 80 between the impellers having passages that direct the air from one impeller to another, a cooling water chamber in the diaphragm that is arranged on one side of the passage and is sub-divided into a plurality of separate compartments by radially extending walls, partitions in the compartments that direct the cooling water from one end thereof to the other in a zigzag channel whose sections are radially disposed and connected 85 adjacent to their inner and outer ends, a cooling water chamber in the diaphragm that is arranged on the opposite side of the passage, and guide vanes that extend across the passage, there being passages 95 through the guide vanes that connect the zigzag channel with said second chamber so that water from one compartment flows through vane passages arranged in parallel to the chamber and from said chamber 100 through other vane passages arranged in parallel into the next compartment.

11. In a centrifugal compressor, the combination of a casing, rotary impellers arranged within the casing, diaphragms that 105 extend across the casing between the impellers and have passages for conveying air from one impeller to another, cooling water chambers in the diaphragms that are arranged on opposite sides of the passages, 110 and guide vanes in the passages, there being passages through the vanes that extend between the oppositely disposed chambers, said vane passages being arranged in parallel relation with respect to the flow through 115 them.

In witness whereof, I have hereunto set my hand.

WALTER KIESER.
